UNITED STATES PATENT OFFICE

CLARENCE E. LOMAX, OF OAK PARK, AND JOHN H. VOSS, OF BEBRYN, ILLINOIS, AS
SIGNORS, BY MESNE ASSIGNMENTS, TO ASSOCIATED ELECTRIC LABORATORIES, INC.,
OF CHICAGO, ILLINOIS, A CORPORATION OF DELAWARE, **INTERCOMMUNICATING SYSTEM**

Application filed May 12, 1930. Serial No. 451,610

The present invention relates in general to intercommunicating systems, but is particularly concerned with the provision of a system of this character provided with one or more trunk connections to an outside exchange. The present invention relates in general to hookswitch springs 12 of station No. 1 to battery. The attendant at station No. 1, upon removing his receiver 11, at springs 12 opens the traced signalling circuit, and at springs 13 completes the talking circuit between the two stations. Talking battery is supplied

The main object of the invention is to provide a convenient and economical arrangement of circuits and apparatus enabling the establishment of one or more trunk connections between the intercommunicating system and an outside exchange. The invention also provides for the connection of two stations, the trunk battery is supplied to the respective stations through the impedance coil 16 at station No. 1, and the party at station No. 3 desires to communicate with a party at station No. 2, in lieu of station No. 1, the operation is the same except that, the station-selecting arm 34 is moved into position with its No. 2 contact

The invention is disclosed in a single sheet of drawings, comprising Figs. 1 and 2, which diagrammatically disclose sufficient telephone apparatus and circuits to enable the party at station No. 3 to move into connection with its No. 2 contact prior to the pressing of button 36. If the party at station No. 3 desires to extend a connection to the outside exchange, he

invention to be readily understood. The equipment to the left of the dotted vertical line comprises the incoming end of 20 a trunk line extending from the outside exchange and the associated equipment for giving answering supervision to the attendant at the answering station of the intercommunicating system.

simply moves the station selecting wiper 34 to the trunk contact 5, and in so doing, completes an operating circuit for the relay A, which, at its upper contacts, completes a direct current bridge across the trunk conductors extending to the main exchange, thereby causing the operation of the calling signal at the operator's position of the main exchange in

25 To the right of the vertical dotted line are shown three substations of the intercommunicating system, the No. 1 station having associated therewith a hold key 50, it being assumed that that station is the one designed to receive all incoming calls. The circuit for relay A extends from ground on the transmitter 30, through the receiver 31, springs 33, selecting wiper 34 and its trunk contact 5, over the trunk conductor extending to the left of the dotted vertical line, the lower right-hand

It is believed that the invention will be better understood by giving a description of the winding of relay A, and the upper right-hand winding of the repeating coil to the operation of the system, and for this purpose, it will first be assumed, that the party ungrounded pole of the battery. The opera-

35 at station No. 3 desires to extend a connection to station No. 1. To do this, the party at station No. 3 first removes the associated receiver 31 from the switchhook. The removal of the completes the connection in any desired man-

40 receiver from the switchhook causes springs 32 to open, thereby opening a point in the signalling circuit of the buzzer 35 associated with station No. 3, and at 41 springs 33 closes a point in the signalling circuit of the buzzer 35 associated with station No. 3. In a trunk connection the station No. 3 obtains its talking current through the re- 42 peating coil and relay A. All stations are connected in like manner.

point in the talking circuit to station No. 1, to the incoming trunk and, therefore, any station No. 1 is now signalled by the party at station may answer an incoming call. However, 45 station No. 3, pressing button 36. The press, even, since only the station No. 1 is equipped with a hold key 50, this is the only station

buzzer 15 of station No. 1. This circuit extends which can hold the trunk while notifying tends from ground at the button 36, through another wanted station to connect therewith. the station-selecting wiper 34 and its contact. Therefore, the attendant at station No. 1 will 60 1, through the buzzer 15, and through the ordinarily answer all incoming calls.

When the ringer 19 is actuated, the attendant at station No. 1 answers the call by moving the station selecting arm 14 to its trunk contact 5 and removes the receiver. A circuit 5 is now completed from ground supplied through the transmitter 10, the receiver 11, switchhook springs 13, the station selecting arm 14, its trunk contact 5, and over the previously-traced circuit through the relay A to 10 the negative pole of the battery. Consequently, the relay A energizes and, at its upper contacts, completes a direct-current bridge across the trunk to cut off the ringing current and provide answering supervision at 15 the main exchange. The subscriber at station No. 1 can now converse with the calling subscriber and determines the number of the station desired. It will be assumed that station No. 2 is desired. The attendant at station 20 No. 1, accordingly, presses the self-locking hold key 50 to close the circuit of relay B. This relay, upon operating, at its upper contacts, places a shunt about the ringer 19 in multiple with the upper contacts of relay A, 25 so that the relay A may be deenergized without effect so far as the condition of the trunk is concerned. The attendant at station No. 1 now replaces his receiver 11, thereby opening the traced circuit through the relay A, 30 which restores, and at its lower contact sets, completes a holding circuit for the relay B and an energizing circuit for the hold lamp L. The hold lamp glows, to notify the attendant at station No. 1 that the trunk is being held, 35 and that the key 50 may be restored and the party wanted called over the intercommunicating system in the usual manner. The party at station No. 3, upon hearing his station signal 35, before answering moves his 40 station selecting arm to the answering position ANS.

The party at station No. 3, upon being advised that he is wanted on the trunk, simply moves his station selecting wiper 34 to the 45 trunk contact 5, and in so doing, completes the previously-traced circuit through the relay A. Consequently, this relay again energizes and, at its lower contacts, opens the holding circuit of relay B and trunk 50 hold lamp signal L. The extinguishing of the hold lamp indicates to the attendant at station No. 1 that the station wanted has been connected with the trunk. When the party at station No. 3 replaces his receiver, the relay 55 A restores and removes the shunt from across the trunk, thereby giving disconnect supervision to the operator at the outside exchange. While only one trunk connection has been shown, obviously, one or more trunks may 60 be added if required.

If the trunk terminates in an automatic exchange, those subscribers who are to be permitted to make trunk calls are provided with impulse devices connected as illustrated 65 in Fig. 2.

Under these circumstances, when a subscriber wishes to make a trunk call, he places his station selecting wiper on the trunk contact and proceeds to dial the called number of the outside exchange subscriber. The A 70 relay responds and at its upper springs repeats the impulses to the automatic switches of the outside exchange.

From the foregoing, it will be appreciated 75 that applicant has provided a very simple and practical intercommunicating system which may have trunk connections with either or both manual and automatic exchanges.

What is claimed is:

1. In a telephone system a trunk line extending from one exchange to the stations of an intercommunicating system, a signal for said trunk located in the vicinity of said stations and operable from the exchange to notify the parties at the stations that a connection with one of them is desired, a relay having contacts for placing a shunt about the signal to stop its operation and to give answering supervision at the exchange end of the trunk, and means at said stations for causing the operation of said relay incidental to the removal of the receiver at any station. 80

2. In a telephone system a trunk line extending from one exchange to the respective stations of an intercommunicating system, a signal for said trunk located in the vicinity of said stations and operable from the exchange to notify the parties at the intercommunicating stations that a connection with one of them is desired, a relay for placing a shunt about the signal to stop its operation and to give answering supervision at the exchange end of the trunk, means at said stations for causing the operation of said relay incidental to the removal of the receiver at any station, a second relay for placing a shunt about said signal, a second signal under control of said relays, means under the control of one of said stations which has answered an incoming call for causing the energization of the second relay to thereby hold the trunk independently of the first relay, a circuit for said second signal completed by said first relay consequent to the replacement of the receiver to notify the party at the answering station that the trunk is being held, and an operating circuit for the first relay completed by the connection of any station with the trunk to cause the second signal to be deenergized to notify the first answering party that a second station has connected with the trunk. 95

3. In combination with an intercommunicating system in which each station is provided with a station selector and associated contacts for connecting with any other station of the system, and wherein a push button at the calling station may then be operated to signal the selected called station; a 100

trunk line extending from an outside exchange having an inductively connected extension with branches thereof terminating in the respective stations of the intercommunicating system in the same manner as do the lines of the other stations of the system.

4. In combination with an intercommunicating system in which each station is provided with a station selector and associated

10 contacts for connecting with any other station of the system, and wherein a push button at the calling station may then be operated to signal the selected called station; a trunk line extending from an outside exchange and having branches terminating in the respective stations of the intercommunicating system in the same respective relation thereto as do the other lines of the respective stations, and apparatus associated with

20 the trunk under control of the push buttons of said stations to modify the condition of the trunk to signal an operator of the outside exchange when a connection with an outside exchange subscriber is desired.

25 5. In combination with a telephone system wherein all switching necessary to the establishment of local talking connections is accomplished at the substations, a trunk line extending from a distant exchange having 30 branch connections terminating in the switching apparatuses of the stations of such system, and a relay under common control of the switching apparatus of all stations employed by them in answering calls extended over the 35 trunk as well as in establishing trunk connections with the distant exchange.

6. In a telephone system, a trunk line extending from a main exchange and terminating in a branch exchange, a repeating coil, 40 a winding of said repeating coil, a ringer, a condenser and a second winding of said repeating coil in a series bridge across said trunk line at the branch exchange, another winding of said repeating coil in available 45 talking relation to any station of the system, and means for shunting the ringer and condenser out of the bridge across said trunk when the same is taken for use by a subscriber at the branch exchange.

50 7. In a telephone system, a trunk line, a signal in a permanent bridge across said trunk line, a plurality of stations associated with said trunk, means available to any station of said system for placing a shunt across 55 said signal to stop or prevent the operation of said signal, and means operable at one of said stations for rendering said signal again operative after the same has been rendered inoperative by another of said stations.

60 8. In an intercommunicating system wherein the subscribers themselves perform all switching operations at their stations which are necessary to the completion of telephonic connections between said stations,

65 a trunk line having one end thereof terminat-

ing in a main exchange and the other end having inductively connected branches terminating at the respective stations of the intercommunicating system, and circuits and apparatus enabling any station to answer or establish trunk connections through the medium of the inductive connection by the same procedure as followed in establishing interstation connections.

70 9. In combination with an intercommunicating system, a trunk to an outside exchange, and a relay in said trunk operable from a station of the intercommunicating system to signal an operator in case the trunk is connected with a manual exchange, and means also associated with said station for operating said relay to control automatic switches in case the trunk is connected with an automatic exchange.

75 In witness whereof I hereunto subscribe my name this 8th day of May, A. D. 1930.

CLARENCE E. LOMAX.
